HARMONIC GENERATOR SYSTEM

Application filed January 31, 1927. Serial No. 165,000.

This invention relates generally to electrical systems for producing oscillatory energy of high frequency, and has special relation to oscillation generators of the harmonic 5 type.

A broad object of the invention is to provide a source of electrical waves of high and constant frequency.

Another object is to prevent, in a harmonic 10 generator, shifts in the frequency of the fundamental wave.

A feature of the invention is means for modulating, in a simple and effective manner, a harmonic wave produced in a harmonic 15 generator.

In signalling systems it is often necessary to employ electrical oscillations of high radio frequency and short wave length, say below 100 meters. While the ordinary vacuum tube 20 oscillator will operate on a fundamental frequency of below 100 meters wave length, special precautions must be taken in operating such oscillators in order to maintain the frequency sufficiently constant for signalling 25 purposes. As an alternative, it has been proposed to operate an oscillator in such a manner as to produce a number of harmonics in addition to a fundamental frequency. One of the harmonics of the frequency desired is 30 then picked off by a suitable filter circuit and amplified to the desired signal strength. A system of this kind is shown in the copending application of Frederick A. Kolster No. 32,360, filed May 23, 1925, and entitled Radio 35 transmitting system which application is assigned to the same assignee as this application. Application No. 32,360 discloses the novel idea of employing an arc converter to generate a fundamental frequency together 40 with a number of harmonics, in combination with an amplifier for amplifying one of the harmonics of the desired frequency.

A harmonic system possesses the advantage 45 over a simple high frequency oscillator in that no special stabilizing devices are required. An arc converter may be made to produce a constant fundamental frequency of a wave length of say 500 meters, together with harmonic frequencies. Thus a high frequency 50 harmonic from an arc converter will re-

main at substantially constant frequency because the fundamental frequency of the converter remains constant. In practice it has been found that the stability of the amplifier and of the harmonic generator is much affected by the nature of the coupling between the generator circuit and the input of the amplifier. Unless this coupling is properly designed, the harmonic frequency may not remain constant and sudden surges of current 55 may occur in the amplifier input which may even be sufficient to cause injury to the amplifier tube. It has also been found that only certain means of coupling will deliver sufficient energy at the harmonic frequency to 60 be of practical value.

Referring to the drawing:

Fig. 1 is a circuit diagram illustrating a harmonic generator system incorporating the principles of this invention.

Fig. 2 is a circuit diagram showing a modification of the system shown in Fig. 1.

As certain features of this invention are especially applicable to arc converters, I have illustrated in the drawing an arc converter which consists of a pair of arc electrodes 10 supplied from a suitable source of current such as a direct current generator 11. The magnetic blowout field for the arc may consist of a magnet 12 which may also 65 serve as a radio frequency choke. The main oscillation circuit for the converter includes an inductance 13 and capacitance 14 which are connected directly across the electrodes 10. The inductance and capacitance are 70 preferably connected in series and are tuned 75 to resonate at the fundamental frequency of the converter. A converter of this type will not only produce a fundamental frequency but will also produce a number of 75 harmonic frequencies. To pick off one of 80 these harmonics which is at a desired frequency, there is provided another circuit 85 consisting of inductance 16 and capacitance 17, and which is coupled to the main or fundamental oscillating circuit. For best results it has been found that the inductance 90 95 95 16 and the capacitance 17 should be connected in series and directly across or in 100

parallel with inductance 13 and capacitance 14.

As the energy of the harmonic frequency is relatively slight, it is generally necessary to amplify it to the desired strength. Thus there has been shown a conventional type of amplifier which may comprise a vacuum tube or electron relay 18 having a grid 19, filament or electron emission element 20, and plate or anode 21. The input circuit of the amplifier is coupled to one of the reactive elements of the harmonic circuit, as by means of a conductor 23 providing a connection between the grid 19 and the mid-point between inductance 16 and the capacitance 17. Any suitable work circuit may be coupled to the output of the amplifier. Thus in the drawing there has been shown an absorption device 24, such as a radio antenna and ground connection, which is coupled to the amplifier output as by means of transformer 26. The amplifier output has also been shown as locally energized by means of the usual "B" battery 27, and the filament 20 is energized from the usual "A" battery 28. A negative grid bias may be maintained upon the amplifier tube by means of a "C" battery 29 connected across the filament 20 and the negative lead from the arc converter.

While the system as described above is operable under favorable circuit conditions, it has been found that in some cases the arc converter tends momentarily to oscillate at the frequency to which one of the harmonic circuits is tuned rather than upon the frequency of the fundamental circuit. This is due to the tendency of an arc converter when connected to two or more oscillatory circuits of different resonant frequencies, to oscillate upon the resonant frequency of that circuit which has the lowest effective resistance. In case the resistances of the fundamental circuit and one or more of the harmonic circuits are approximately equal, the fundamental frequency of the arc converter may therefore fluctuate between that of one circuit and another with consequent momentary surges of current through the inductance and capacitance 16 and 17, sufficiently heavy in some cases to injure the apparatus and in any case to make the operation of the system ragged and irregular. I have found that these sudden surges of current may be prevented by inserting an additional resistance 31 into the harmonic circuit, this resistance 31 being of sufficient value to make the total resistance of the harmonic circuit definitely higher than that of the fundamental.

It is of course obvious that other amplifiers may be coupled to the arc converter for picking off other harmonics. For example there has been shown a circuit consisting of inductance 32 and capacitance 33 connected

in series and resonant to another harmonic. Amplifier indicated diagrammatically at 36 is likewise coupled to inductance 32, this amplifier supplying an absorption device 37. A resistance 34 is also inserted in series with inductance 32 and capacitance 33 for preventing sudden surges of current at this frequency.

In Fig. 2 I have shown a slightly modified system which also incorporates a novel means for modulating the output of the amplifier. In this case instead of conductively coupling the input of the amplifier to the inductance 16, the amplifier input is inductively coupled by means of a coil 39 which is in inductive relation with inductance 16. For modulating the energy of the harmonic frequency there is provided means for varying the tuning of the harmonic circuit. This may consist for example of a device which provides a varying reactance electrically associated with the harmonic circuit so as to vary the tuning thereof. For example I have shown a device having stationary electrodes 41 in capacitative relation to movable electrodes 42. Electrodes 42 are mounted upon a rotor so as to revolve upon a pivot or shaft 43, so that the capacitance of this device will vary between maximum and minimum limits. Conductors 44 and 45 serve to connect the stationary and rotor electrodes across one of the reactive elements of the harmonic circuit, preferably the condenser 17. As the electrodes 42 are rotated the tuning of the harmonic circuit is repeatedly varied and these variations are repeated in the amplifier output. For coding the output of the amplifier, a key 47 may be inserted in the grid circuit. While the specific form of modulator shown is especially adapted for producing a signal frequency, it is to be understood that the harmonic frequency may be similarly modulated with voice frequencies.

I claim:

1. In a system of the class described, an arc converter tuned to a given fundamental frequency, a circuit coupled to said converter and tuned to a harmonic of said fundamental, said circuit including an inductance and capacitance in series, a resistance in series with said circuit, and an amplifier having its input coupled to said inductance whereby energy at said harmonic frequency is amplified.

2. In a system of the class described, an oscillation generator producing a fundamental frequency and a number of harmonics, a circuit tuned to one of said harmonics and coupled to said generator, an amplifier having its input coupled to said circuit for amplifying said harmonic, and means for varying the tuning of said circuit for modulating the output of the amplifier.

3. In a system of the class described, an oscillation generator having a fundamental

frequency and a number of harmonics, a circuit tuned to one of said harmonics and coupled to the generator, said circuit comprising an inductance and capacitance in series, 5 means for preventing the generator from shifting its fundamental frequency to the frequency of the harmonic to which said circuit is tuned, said means comprising a resistance inserted in series with said circuit, 10 and an amplifier having its input coupled to said circuit.

4. In a system of the class described, an oscillation generator forming a source of waves of frequencies corresponding to a harmonic 15 series, a circuit forming a part of the generator and tuned to the fundamental frequency of said series, a second circuit tuned to a particular harmonic component of said series and coupled to said generator, said second circuit 20 including an energy absorbing element of such value as to prevent shifting of the frequency of the generator to supply current to said second circuit from a different component of said series, and an output circuit coupled to said second circuit.

5. In a system of the class described, an oscillation generator forming a source of waves of frequencies corresponding to a harmonic series, a circuit forming a part of the generator and tuned to the fundamental frequency of said series, a second circuit tuned to a particular harmonic component of said series and coupled to said generator, said second circuit including a series resistance of such value as 35 to prevent shifting of the fundamental frequency of the generator to supply current to said second circuit from a different component of said series, and an output circuit coupled to said second circuit.

40 6. In a system of the class described, an oscillation generator forming a source of waves of frequencies corresponding to a harmonic series, a circuit forming a part of the generator and tuned to the fundamental frequency 45 of said series, a second circuit tuned to a particular harmonic component of said series and coupled to said generator, said second circuit including an energy absorbing element of such value as to prevent shifting of the frequency of the generator to supply current to 50 said second circuit from a different component of said series, and a vacuum tube amplifier having its input circuit coupled to said second circuit.

55 7. In a system of the class described, an oscillation generator producing a wave of a fundamental frequency and a number of harmonics, a circuit tuned to one of said harmonics and coupled to said generator, an amplifier having its input coupled to said circuit 60 for amplifying said harmonic, and means for varying the impedance of said circuit for modulating the output of said amplifier.

8. A source of oscillations comprising an oscillation generator producing waves of a

fundamental frequency and harmonics thereof, and a circuit tuned to one of said harmonics and coupled to said generator, said generator being characterized in that it can shift its fundamental oscillation frequency to that of said circuit, and said circuit being characterized in that sufficient resistance is introduced therein to prevent such a shift in frequency.

In testimony whereof, I have hereunto set 75 my hand.
